United States Patent Office.

DANIEL S. COLBY AND ROBERT SCORER, OF TROY, NEW YORK, ASSIGNEES TO EDWARD J. HICKS AND GURDON G. WOLFE, OF SAME PLACE.

Design No. 2,964, dated March 31, 1868.

DESIGN FOR THE LEG AND DOOR OF A STOVE.

The Schedule referred to in these Letters Patent and making part of the same.

TO ALL WHOM IT MAY CONCERN:

Be it known that we, DANIEL S. COLBY and ROBERT SCORER, each of the city of Troy, in the county of Rensselaer, and State of New York, have jointly invented or produced a new and original Design for Stove Plates or Castings, of which the following is a full and exact description, reference being had to the accompanying photographs, in which—

Figure 1 represents a door, and

Figure 2 a leg of a stove having our said design.

Our design for the door consists of the compound ornament D, arranged on the middle portion, and ornamental mouldings E along the border of the surface F of the door, so as to appear as represented in fig. 1 and the design for the leg consists of cross-bands, g, on the central swelling surface h, with ornamental foot and flanks j j, as shown in fig. 2.

What we claim as our invention or production, and desire to secure by Letters Patent, is—

The design for a door and leg of a stove, herein set forth and shown.

In testimony whereof, we have hereunto set our hands, this 11th day of February, 1868.

DAN'L S. COLBY,
ROBERT SCORER.
